**METHOD OF COATING A POROUS
WEB WITH INK**

Robert A. McRae, Old Tappan, N.J., assignor to Bur-
roughs Corporation, Detroit, Mich., a corporation of
Michigan

Filed July 16, 1962, Ser. No. 209,912
3 Claims. (Cl. 117—111)

This invention relates to coating apparatus, and to
multiple roll apparatus for coating a fluid substance on
a web.

At the present time, there are many types of multiple
roll apparatus available for applying decorative, pro-
tective, or useful coating on a substrate such as a web
of paper or the like. In general, such apparatus may be
used with many different types and qualities of webs and
coating materials. However, each coating apparatus has
a limit with respect to the thinness of web material which
may be coated. Considering, for example, apparatus for
preparing carbon paper by coating an ink on a paper web,
known apparatus cannot be used in mass production for
applying a coating of ink to a highly porous paper, such
as twisting tissue. It has been found that, when an ink
is coated on an extremely porous paper of this type, the
ink passes through the paper and gradually accumulates
on the roll which supports the paper. Eventually, such
accumulation causes wrinkles and other non-uniformities
to develop in the coated paper.

Accordingly, the objects of the invention are con-
cerned with the provision of improved apparatus for
applying coatings to thin and porous web material.

Briefly, the apparatus of the invention includes means
for transferring coating material from a source to the
web material. This means includes a transfer roll which
applies the coating ink directly to the web. Means are
also provided for feeding the web material from a supply
reel to the coating transfer means. This means includes
a feed roll on which the web is carried as it is contacted
by, and coated by, the transfer roll. According to the in-
vention, a plurality of thicknesses of the web material is
passed through the coating region between the transfer
roll and feed roll so that the coating material cannot pass
through the web and onto the surface of the feed roll.

The invention is described in greater detail by reference
to the single figure of the drawing which is an elevational,
schematic view of apparatus embodying the invention.

Coating apparatus 10 embodying the invention may be
used for applying a coating of a transfer material, such
as an ink, to a paper web, and the following description of
the invention is directed toward this use of the apparatus.
However, it will be clear to those skilled in the art that
the invention may also be used for applying many differ-
ent types of coating materials to many different types and
qualities of webs other than that specifically described.
The invention is particularly useful for applying coatings
on extremely porous papers, an operation which has not
been possible in the past.

Coating apparatus 10 embodying the invention is shown
in the drawing and includes a supply reel 14 of paper 16
to be coated, which, for optimum operation and sim-
plicity, is mounted directly beneath the means for applying
coating material to the paper. The apparatus 10 also
includes a suitable source (not shown) of ink which is
transported by any convenient number of rolls (not
shown) to a rotatable ink transfer roll 20. The transfer
roll, preferably, has a soft, resilient surface, which may be
provided by a blanket of synthetic rubber, such as ne-
oprene, having a hardness of approximately 80 to 90
durometers. The transfer roll is provided with a shaft
24 on which it rotates and which is preferably hollow so
that a temperature-controlling fluid may be circulated

2

through the roll. The shaft 24 may also carry at its ends
suitable gears 30, or the like, by which it may be rotated.
The transfer roll 20 is suitably supported by means not
shown for vertical and horizontal adjustment to regulate
the pressure of its contact with the adjacent web-feeding
roll 34.

The web-feeding roll 34 is positioned adjacent to, and
preferably horizontally axially aligned with, the transfer
roll 20. Roll 34, preferably, has a hard surface, for
example of stainless steel, and is also provided with a
shaft 40 which carries gears 42, or the like, by which
the shaft is rotated. The shaft 40 is also preferably hollow
so that a temperature-controlling fluid may be cir-
culated through the roll 34. A plurality of chill or idle
rolls 46 are mounted adjacent to, and following, the feed
roll 34, if such are required. Any suitable number of
guide rolls (not shown) may also be provided for lead-
ing the web, after being coated, to a takeup reel 50
which is suitably coupled to, and driven by, a motor 54.
The motor, or other power source, is also suitably coupled
to the transfer roll 20 and web-feeding roll 34, which are
positively driven thereby. This coupling is represented
by dash lines 35.

According to the invention, in order to coat ink on a
paper 16 which is very porous, the paper is fed from the
supply reel 14, between the ink transfer roll 20 and web-
feeding roll 34, over the feed roll and back to and over
the supply reel, between the transfer and feed rolls again,
and finally over the various chill and guide rolls to the
takeup reel 50.

With this arrangement for threading the paper, a
double thickness of paper is present in the area where the
coating operation occurs, between the rolls 20 and 34.
Thus, if any coating material penetrates through the
first layer of paper 16' as it is applied thereto, it is ab-
sorbed by the second layer 16'' of paper underneath and
is thus prevented from reaching the roll itself. It is to
be noted that the coated surface of paper 16 can be trans-
ported without contacting any of the rolls of the apparatus
10.

For optimum performance of the coating operation
and to allow minimum penetration of coating material
into the paper being coated, the feed roll 34 is operated
at a relatively low temperature, for example 60 to 70° F.,
or the like. The desired temperature may be achieved,
for example, by flowing a suitable fluid from a source
70 through hollow shaft 40 on which the roll rotates.
The operating temperatures of the other rolls of the ap-
paratus may be adjusted in similar fashion. Means for
obtaining temperature control are well known and are
not shown in detail.

The present invention has the important advantage that
it allows the coating of thinner and more porous, and thus
more inexpensive, paper than could be coated in the past.
As an example, one type of coating apparatus which
55 could previously provide a coating of desired weight on
paper no thinner than kraft paper can now coat the same
weight of ink on twisting tissue. In this case, a saving of
about ten cents per pound in the paper is realized.

It is clear from the foregoing description of the in-
vention that the principles thereof are broadly applicable
to other types and arrangements of coating rolls and the
like than that described. In addition, the principles of the
invention apply to different types of coating materials
and different types of web materials.

65 What is claimed is:

1. The method of coating a porous web with an ink
comprising the steps of
mounting a coating roll adjacent to a support roll,
the support roll being adapted to support a web to be
coated and the coating roll being adapted to apply
ink material to the web,

mounting a supply roll of web material adjacent to said coating roll and supply roll,
applying uncoated web material from said supply roll in a plurality of layers over said support roll,
and then applying ink to the top layer of the plurality of layers of webs supported by said support roll. 5

2. The method of coating a porous web with an ink comprising the steps of
mounting a coating roll adjacent to a support roll,
the support roll being adapted to support a web to be 10
coated and the coating roll being adapted to apply ink material to the web,
mounting a supply roll of web material adjacent to said coating roll and said support roll,
leading said web from said supply roll over said support roll, 15
passing said web over the surface of said support roll and then again passing said web over said support roll whereby two layers of uncoated web are present on the surface of said support roll,
and then applying ink to the top layer of the webs supported by said support roll. 20
3. The method of coating a porous web with an ink comprising the steps of
mounting a coating roll adjacent to a support roll,
the support roll being adapted to support a web to be 25

coated and the coating roll being adapted to apply ink material to the web,
mounting a supply roll of web material adjacent to said coating roll and said support roll,
leading said web from said supply roll over said support roll,
passing said web over the surface of said support roll and then again passing said web over said support roll whereby two layers of uncoated web are present on the surface of said support roll,
then applying ink to the top layer of the webs supported by said support roll,
and then winding the top layer of coated web on a takeup reel. 5
